UNITED STATES PATENT OFFICE.

JOHN KELLY, OF JAMAICA PLAIN, MASSACHUSETTS.

SEWER-CLEANING DEVICE.

1,117,192.

Specification of Letters Patent. Patented Nov. 17, 1914.

Application filed September 9, 1912. Serial No. 719,297.

To all whom it may concern:

Be it known that I, JOHN KELLY, a citizen of the United States, and a resident of Jamaica Plain, in the county of Suffolk and 5 State of Massachusetts, have invented an Improvement in Sewer-Cleaning Devices, of which the following description, in connection with the accompanying drawings, is a specification, like characters on the drawings representing like parts.

This invention relates to improvements in sewer cleaning devices of that class in which ropes, cables, chains or the like, are utilized to move longitudinally through the sewer 15 or pipe a valved device which in one direction of its movement permits free passage of the sewage therethrough, and which in the opposite direction closes and carries with it the sewage.

20 My invention will be best understood by reference to the following specification, when taken in connection with the accompanying illustration of one specific embodiment thereof, while its scope will be more 25 particularly pointed out in the appended claims.

In the drawings:—Figure 1 is an end elevation of a sewer cleaning device embodying my invention, with the cable attaching 30 means partly broken away; Fig. 2 is a longitudinal section on line 2—2 of Fig. 1; and Fig. 3 is a detail longitudinal section showing a modification of the cable-attaching device.

35 Referring to Figs. 1 and 2 of the drawings, and to the embodiment of my invention which I have there disclosed for illustrative purposes, I have there shown a sewer cleaning device having a wall, generally 40 designated by the numeral 4, having an aperture or passage therethrough, said wall being preferably composed of two members 6—6, herein in the form of rings, between which there is interposed flexible means in 45 the form of a flexible marginal flange or flap 7, which extends laterally from the circumference of said rings. This flexible flange or flap may be made of leather or other suitable material, but is preferably 50 made of rubber. The flange or flap is preferably inclined toward one side of the wall 4, and preferably has a reverse curve formation, so that when the device is drawn in one direction (toward the left, Fig. 2), through 55 the sewer or pipe, the flange or flap will

bend very freely and allow a perfectly free passage of the device through the pipe. When, however, the device is drawn through the sewer or pipe in the opposite direction, and the aperture 5 is closed by suitable 60 means, the flange or flap 7 is forcibly pressed against the inside of the sewer or pipe by the combined action of the forward movement of the device and the pressure of the pent up sewage against the flange, as 65 will be evident by an inspection of the dotted line position of the flange shown in Fig. 2. The aperture 5 may be opened in one direction of the movement of the device and closed in the opposite direction of movement by suitable means, preferably in the 70 form of a check valve automatically opening and closing, according to the direction of movement of the device through the sewer. Herein this valve is in the form of 75 a pair of gates 8—8, mounted upon hinges 9—9 and having their marginal portions overlapping, or lying against one face of the adjacent ring 6, in such a manner that while capable of swinging freely to an open position (toward the right, Fig. 2), they cannot swing any farther toward the left from the position illustrated in Fig. 2. These gates, it will be observed, open in the direction toward which the flange or flap 7 is inclined, 85 and consequently when the device is drawn in the opposite direction (toward the left, Fig. 2), the gates automatically open under the influence of the sewage and the flange or flap contracts or recedes from the sides 90 of the pipe or sewer, and the device passes freely through the sewer. When, however, the device is moved in the opposite direction, the gates 8 will automatically close and the flange or flap will be firmly pressed 95 against the inner surface of the pipe, and will thus afford an exceedingly efficient means for scraping the collections of sewage from the sides of the sewer or pipe. The device is particularly well adapted for use 100 in performing a final cleaning operation following the operation of the apparatus disclosed in my prior Patent, No. 896,835, dated August 25, 1908.

The device may be provided with any 105 suitable manipulating means for moving the same to and fro within the sewer or pipe, but I preferably employ for that purpose cable attaching means in the form of two reticulated or apertured structures desig- 110

nated generally by the numerals 10—10. Each of these structures may be formed of a plurality of flat bars 11, herein four in number, preferably arranged in the form of 5 a pyramid, and having inwardly projecting lugs 12, to facilitate their attachment to the wall 4. As a convenient means for attaching these lugs to the wall, I preferably employ a plurality of bolts 13 passing through 10 the lugs, through the rings 6, and through the flange or flap 7, thus not only securing the structures 10 to opposite sides of the wall, but also serving to secure the rings to 15 each other, and clamp the flange or flap therebetween. The other ends of each set 20 of bars 11 may be brought together and secured to one another in any suitable manner. In Fig. 2, I have shown the ends of four flat faces of a block 14, to which the 25 bars are secured by bolts 15 and 16 passing at right angles to each other through the block. The bolt 16 may also serve as a convenient means for attaching an eye or the like 17 to receive a rope, cable, chain or the like. It will be understood that in the appended claims where I have used the words 30 "cable attaching means," the word "cable" is used in its broad signification, meaning any equivalent flexible member. It will be observed that the bars converge toward the median axial line A—A of the device, and the eyes 17—17 are placed upon this line so that when the cables are attached to the 35 eyes, the force which is exerted to pull the device to and fro will be along the line A—A, and the device will consequently tend to maintain its axis substantially coincident with the axis of the sewer or pipe.

40 Referring to Fig. 3, I have shown therein a modification of the cable attaching means in which I employ bars 18—18 and bars 45 19—19, the latter being given a quarter twist, so that the terminal portions of all four bars may be laid together flatwise, thus permitting an eye 20 to be attached thereto by a single bolt 21 passing through all four

of the bars, without the use of a block such as is shown in Fig. 2.

While I have herein shown and described 50 one specific embodiment of my invention for illustrative purpose, and have disclosed and discussed in detail the construction and arrangement incidental to one specific application thereof, it is to be understood that the 55 invention is limited neither to the mere details or relative arrangement of parts nor to its specific embodiment herein shown, but that extensive deviations may be made from the illustrated form or embodiment of the 60 invention, without departing from the principles thereof.

Having thus described my invention, what I claim and desire by Letters Patent to procure is:—

65

1. A sewer pipe cleaning device having, in combination, means comprising a pair of plates having a passage therethrough, means for closing said passage, flexible means projecting laterally from between the plates of 70 the first-mentioned means and having an incline toward one side of the latter and adapted to engage the pipe at an abrupt angle thereto for directing the sewage inwardly toward said passage, and manipulating 75 means secured to opposite sides of the first-mentioned means.

2. A sewer cleaning device having, in combination, means having a passage therethrough, means for closing said passage, 80 flexible means projecting laterally from the first-mentioned means said flexible means having a reverse curve formation and being inclined toward one side of the first-mentioned means, and manipulating means secured to opposite sides of the first-mentioned means.

In testimony whereof, I have signed my name to this specification, in the presence of two subscribing witnesses.

JOHN KELLY.
